UNITED STATES PATENT OFFICE.

WILLIAM F. PILLMORE AND DAVID ANDEREGG, OF WESTERNVILLE,
NEW YORK.

PEA-HULLING MACHINE.

SPECIFICATION forming part of Letters Patent No. 752,256, dated February 16, 1904.

Application filed September 30, 1903. Serial No. 175,213. (No model.)

To all whom it may concern:

Be it known that we, WILLIAM F. PILLMORE and DAVID ANDEREGG, citizens of the United States, residing at Westernville, in the county 5 of Oneida and State of New York, have invented a new and useful Pea-Hulling Machine, of which the following is a specification.

This invention relates to machines for hulling peas, and it is an improvement on the machine of this class for which Letters Patent of the United States No. 728,759 were granted to us on the 19th day of May, 1903.

In the said Letters Patent is presented a separating - drum supported revolvably and 15 presenting an unobstructed interior, a plurality of beater-drums disposed longitudinally within and rotating in the same direction as the separating-drum and distributed about its central or axial space and provided with ribs 20 or beating devices, vine-lifting ribs upon the inside of the separating-drum, and means for feeding the vines into the central space between the beater-drums, which constitutes a conveyer - channel through which the vines 25 mainly travel during their passage through the machine. While the construction thus generally expressed has been found extremely useful and while it has been found to operate to perfection upon pea-vines under ordinary 30 circumstances, we have discovered that a superior result may be attained by certain changes, which are the subject of the present application. These changes consist, first, in making the beater-drums frustum-shaped in 35 stead of cylindrical, as shown in our patent above referred to, the vines being fed between the wide ends of the frustum-shaped beater-drums. This construction is especially useful when the vines that are operated upon are 40 quite long, inasmuch as said vines during the operation of the machine are apt to and, in fact, are intended to escape from the central space between the beater-drums into the space between said beater-drums and the exterior cylinder. Now when short vines are operated 45 upon these will readily return into the central space, where they are subjected to the most violent action of the beaters or agitators. Long vines, however, will not return so readily

into the space where they will be subjected to 50 the most efficient action of the machine, and consequently the operation to that extent will be imperfect. To avoid this difficulty, we now make the beater-drums frustum-shaped—of decreasing diameter toward the discharge end 55 of the machine—we having found by practical experience that the increasing distance between the perimeters of the beater-drums will greatly facilitate the ingress between them of the material to be operated upon.

Secondly, our patented device is improved by disposing the lifting-ribs upon the inside 60 of the exterior cylinder in a somewhat inclined position, whereby we find that the operation will be facilitated.

Thirdly, our improvement contemplates the disposition beneath the separating-drum of a plurality of endless aprons, which will serve to separate from the peas any impurities in the way of chaff, small pieces of pods or vines, 70 dirt, and the like which it is extremely desirable to separate from the peas at as early a stage as possible.

Our invention, then, consists in the improved construction, arrangement, and combination 75 of parts, which will be hereinafter fully described, and particularly pointed out in the claims.

In the accompanying drawings, Figure 1 is 80 a vertical longitudinal sectional view taken through a machine constructed in accordance with our invention. Fig. 2 is a transverse sectional view of the same, taken on the line 2 2 in Fig. 1.

Corresponding parts in both figures are in- 85 dicated by similar numerals of reference.

1 designates a suitably-constructed frame, in which are journaled rollers 2, supporting the separating-cylinder 3, which is provided with a plurality of perforations 4 of suitable 90 diameter to permit the peas to escape therefrom. This cylinder and its exterior surface may be constructed of any suitable material. Interiorly upon the cylinder are disposed a plurality of vine-lifting ribs 5, which are disposed obliquely, as shown, and which when the machine is in operation have a screw action, which assists in delivering the vines ele-

vated by said lifting-ribs in the direction of the central line or axis of the cylinder. Suitably disposed within the cylinder and in bearings provided therefor in the frame of the 5 machine are a plurality of shafts 6, three of which appear in the accompanying drawings. We would desire it to be understood, however, that more than three of these shafts and their related parts may be utilized without departing 10 from the spirit of the invention. These shafts, it will be observed, are disposed equidistantly apart and all at equal distances from the axis of the separating-cylinder. These shafts 6 carry the beater-drums 7, which instead of being cylindrical, as in our former 15 patent, are made frustum-shaped; their large ends being disposed at the feed end of the machine, where a hopper 8 is provided for the purpose of feeding the material operated 20 upon into the space between the beater-drums. It is obvious that owing to the decreasing diameter of the latter toward the discharge end of the machine the space between said drum increases gradually and that consequently 25 the vines, which during the operation of the machine are operated upon mainly while disposed in the said central space, will be readily returnable into said central space in the event of their having found an exit between 30 any two of the beater-drums into the space between the latter and the exterior cylinder.

The discharge ends of the beater-drums are extended beyond the discharge end of the separating-cylinder for the purpose of discharging 35 the halm beyond said cylinder, and the shafts of said drums are provided with pulleys to receive motion from any suitable source of power, whereby they and the separating-cylinder may be rotated simultaneously in the 40 same direction.

Under the provisions of our former patent the separating-cylinder was disposed above a trough or casing forming a receptacle for the 45 peas. We now arrange under the separating-cylinder a pair of endless carriers 9 and 10, consisting of wide aprons mounted upon suitable rollers 9^a and 10^a, the lower end of the endless apron or carrier 9 being disposed slightly above the lower end of the apron 10. A third 50 apron 11 is mounted upon rollers 11^a beneath the discharge end of the apron 10, said apron 11 inclining in the direction of a receiver 12. It is obvious that when the machine is in operation the peas will drop upon the aprons 9 55 and 10, the upper leads of which move in an upward direction. The peas being round will roll down the said aprons, those dropping upon the apron 9 rolling over upon the lower end of the apron 10 and passing from thence 60 to the apron 11, which is disposed at a somewhat less inclination than the aprons 9 and 10. Bits of stalks, pods, and the like will adhere to and be carried upward by the aprons 9 and 10 and be discharged at the upper 65 ends of the latter into suitable receptacles

or places of deposit, scrapers or brushes being employed, if necessary, in order to remove the waste matter. The final separation of the peas from objectionable matter will take place upon the apron 11, which being 70 disposed at a less inclination than the aprons 9 and 10 will make it practically impossible for waste material to escape into the receptacle provided for the peas.

In practice the outer drum and the beater-drums are all driven in the same direction, as will be found indicated by arrows or darts upon Fig. 2 of the drawings, said beater-drums being rotated at a relatively high rate of speed, as shown by the heavy darts. 80

The operation of the device is as follows: The pea-vines are fed into the chute or hopper 8, passing from thence into the space between the rapidly-rotating beater drums or cylinders. No care need be taken to feed the 85 material slowly or evenly, inasmuch as as soon as a bunch of the vines enters the space between the beater-drums it will be violently torn asunder and subjected to the threshing action of the beaters. When, as in the present instance, three beater-drums are used, the material fed between said drums will be forced by the action of each drum in an outward direction toward the outer drum. A portion of the vines will pass into contact with said 95 outer drum. The greater proportion, however, will adhere to the beaters and be carried over or around the latter into the central space. It will also be seen that such portion of the vines as passes into contact with the 100 inside of the outer drum will be elevated by the ribs of the latter until it reaches a point even with or slightly above the uppermost drum, the screw action of the ribs serving to elevate the front ends of the vines. The tendency of the vines will be to drop upon said 105 drum and the tendency of the beaters upon the latter will be to carry the vines into the central space between the drums. The tendency of the beaters upon the one drum to 110 seize the vines and throw them outward against the inner wall of the outer drum will be counteracted by the beaters upon the next, the tendency of which will be to throw the vines toward the next succeeding. It will 115 thus be seen that the vines and pods, by the combined action of the several drums, will be violently threshed and agitated and that the 120 tendency of the combined action of the three inner drums will be to retain the vines or 125 halm between the said drums. It is not intended thereby to assert that the vines, pods, &c., are retained entirely in the space between the said beater-drums, but by far the larger proportion is thus retained and will be progressively fed toward the discharge end of the machine, while the smaller and especially the heavier particles, including necessarily the shelled peas, will escape to the outer drum, through the perforations of which they 130

pass to the cleaners. Thus while the agitation to which the pea-vines is subjected is excessive from a standpoint of rapidity of action the beating they receive does not result in any damage, such as bruising or mashing of the peas, they being protected by the halm, from which they are readily separated and permitted to pass to the outer drum. The disposition of the ends of the beater-drum with relation to the outer drum—*i. e.*, their being projected beyond the outer drum—operates to prevent entanglement of the vines with parts of the machine.

We desire it to be understood that while we have in the foregoing described a simple and preferred construction of our improvement, we do not thereby necessarily limit ourselves to the precise structural details herein shown, but reserve the right to any changes, alterations, or modifications which may be resorted to within the scope of our invention and without departing from the spirit or sacrificing the utility of the same.

Having thus described our invention, we claim—

1. In a machine of the class described, a separating-drum supported revolubly and presenting an unobstructed interior, a plurality of frustum-shaped beater-drums disposed longitudinally within and rotated in the same direction as the separating-drum and distributed about its central or axial space, said beater-drums being provided with beater-ribs and said beater-drums being disposed with their large ends at the feed end of the machine and decreasing in diameter toward the discharge

end of the machine, vine-lifting ribs disposed obliquely upon the inside of the separating-drum, and means for feeding the vines into the central space between the beater-drums, which constitutes a conveyer-channel through which the vines mainly travel during their passage through the machine.

2. In a machine of the class described, the combination of an external drum adapted to revolve and provided with interiorly-disposed oblique vine-lifting ribs, and a plurality of interior beating and conducting drums arranged inside thereof, equidistantly from each other and equidistant from the axis of the external drum, said beater-drums being frustum-shaped and disposed with their large ends at the receiving end of the machine.

3. In a machine of the class described, the combination of a perforated separating-drum, a plurality of frustum-shaped beater-drums disposed within the same, equidistantly from each other and equidistant from the axis of the separating-drum, oppositely-inclined endless carrying-aprons disposed underneath the separating-drum, one of said aprons terminating slightly above the lower end of the other, and an auxiliary cleaning-apron disposed beneath the discharge ends of the above carriers.

In testimony that we claim the foregoing as our own we have hereto affixed our signatures in the presence of two witnesses.

WILLIAM F. PILLMORE.
DAVID ANDEREGG.
